UNITED STATES PATENT OFFICE

AUGUST MEYERHANS, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND

ELECTRIC TRANSFORMER

Application filed June 12, 1929, Serial No. 370,175, and in Germany October 31, 1928.

This invention relates to improvements in electric transformers and, more particularly, to transformers which do not require lead-in bushings for the high voltage side.

5 Many efforts have been made to eliminate the lead-in insulating bushings heretofore considered necessary for the high-voltage side of transformers for the reasons that such bushings are very expensive and require 10 a great amount of space which is often difficult to provide. For the purpose of eliminating such bushings, it has been proposed to make the entire tank of insulating material. Heretofore, however, such insulating tanks were impractical because they 15 were more expensive than the usual iron tanks with the lead-in bushings, or because of difficulties in the construction of such tanks.

20 One of the objects of the present invention, therefore, is to provide an improved electric transformer construction which will not require lead-in bushings.

Another object of the invention is to provide 25 a transformer without lead-in bushings for which the tank need be only partially formed from insulating material.

A further object of the invention is to provide 30 a transformer having the portion of the side walls of the tank adjacent the high voltage winding formed of insulating material.

A further object of the invention is to provide 35 a transformer structure having the exterior walls thereof partially formed of insulating material which is coextensive only with the height of the high voltage coils thereof.

Another object of the invention is to provide 40 in electric transformer apparatus, means for producing an equal potential drop per unit of length over the insulating casing surrounding the primary winding, to avoid flash-overs or creepages over the outer surface thereof.

Objects and advantages, other than those above set forth, will be apparent from the following description and the drawings, in which

45 Figure 1 is a cross-sectional view of an

electric transformer embodying the present invention; and

Figs. 2 to 5 are similar views, showing various modifications of the invention.

Referring more specifically to the drawing 55 by characters of reference, the reference numeral 10 indicates the bottom portion of a tank which may be made of iron or any other suitable material and which is provided at its upper edge with a groove 11, the purpose of which will hereinafter appear. A cylinder 12, of insulating material having suitable mechanical characteristics and of substantially the same internal dimensions as bottom 10, is placed in groove 11 in such manner as to form a continuation 60 of the bottom portion 10. A top portion 13, provided with a groove 14 along the lower edge thereof for engagement with insulating cylinder 12, completes the tank 70 which is closed by a suitable cover 16. The joints or connections between cylinder 12 and the cylinder portions 10 and 13 are sealed tight in any suitable manner to prevent leakage of oil or other insulating 75 medium with which the tank might be filled. The tank is so proportioned that cylinder 12 closely surrounds the internal structure of the transformer, to be hereinafter described, for the purpose of producing a similar potential drop per unit of length over the exterior surface of the cylinder in the direction 80 of the longitudinal axis therethrough.

A plurality of insulating members 17 arranged within and resting upon the tank 85 bottom 10 support a core 18. A secondary winding 19 and a primary winding 21 are, as shown, concentrically arranged on one leg of the core 18. The windings may, of course, be divided and arranged on the several legs of the transformer in any suitable manner as will be hereinafter described. The leads of the primary winding are connected directly to the bottom 10 as at 22 and to the top 13 as at 23 without the use 90 of any cumbersome and expensive insulating bushings. Terminals (not shown) for the high-voltage winding are secured to the tank top portion 13 or the cover 16 and to the tank bottom portion 10 at the points found 95 100

most convenient when installing the transformer. The secondary winding connections are preferably brought out of the tank through the bottom portion 10 by means of small tubes of insulating material, as shown, 5 sealed to the tank in a liquid tight manner.

When the windings are concentrated on one leg of core 18, a plurality of split metallic potential-dividing rings 24 are arranged 10 about the unwound leg of the core at equidistant points along the longitudinal axis thereof to secure equal potential drop over the entire length of the windings whereby flash-overs and creepages over the surfaces 15 of cylinder 12 may be avoided. The potential dividing rings 24 may also be arranged to surround core 18 and windings 19 and 21, as shown in Fig. 2. The potential dividing rings 24 may be supported from the inner surface of the insulation 12 but are 20 preferably embedded in grooves in a wooden frame 26 arranged about the unwound leg of the core 18 and held between the cover 16 and the bottom of the tank.

25 The use of potential-dividing rings 24 may be avoided by dividing the windings into two series-connected portions as shown in Fig. 3, in which the primary windings are indicated at 21, 21a and the secondary windings are indicated at 19, 19a. In this construction, the several portions of the windings are arranged alternately on the several legs of the core to provide for an equal potential division without the use of rings 24. 30 35 The primary and secondary windings may also be connected as shown in Fig. 4, in which primary portions 21, 21a and secondary windings 19, 19a are connected in parallel and are arranged in different directions around the core.

40 The low voltage winding may also be arranged on one end of the core, as shown in Fig. 5, rather than being arranged concentrically with the high voltage winding 45 as shown and previously described. In such modified form of the invention, a compensating winding, divided into two portions 27 and 27a, is arranged adjacent both the high voltage winding 21 and the low voltage 50 winding 19 which is arranged in spaced relation on the core 18 beside the high voltage winding 21. The use and purposes of the compensating winding, 27a will be well understood by those skilled in the art. The 55 potential dividing rings 24 are arranged and fitted on the frame 26 as above described and are each connected with the coil forming the high-voltage winding for the purpose of obtaining a gradual potential drop 60 from the supply to the ground potential. In this case the center of the high-voltage winding may be connected either directly or by means of a potential-dividing ring with the active iron core.

65 From the foregoing it will be seen that

the present improved construction or arrangement requires no expensive and space-consuming lead-in bushings such as have been necessarily embodied in transformer apparatus. Such bushings of this general 70 type proposed heretofore are usually made of porcelain and must be carefully protected from all impacts, which gives rise to further difficulties in the handling of transformers constructed heretofore. The use of insulating portions in the tanks of transformers 75 may be extended even to transformers for high voltages due to the use of voltage-dividing rings whereby flash-overs and creepages between the high-voltage leads are 80 eliminated. The invention is therefore not restricted to transformers of any particular size nor even to transformers but may be used for other electrical apparatus ordinarily requiring lead-in bushings. 85

Although but a few embodiments of the invention have been illustrated and described, it will be understood that various other embodiments are possible, and that various changes may be made without departing from the spirit of the invention or the scope of the claims. 90

The invention claimed is:

1. In a tank for electrical apparatus, a metallic member forming the bottom of the tank, a member formed of insulating material and forming an extension of said tank bottom, a metallic member forming an extension of said insulating member, and a top member forming a cover for the tank. 95 100

2. In a tank for electrical apparatus, a dished metallic member forming a bottom portion for the tank, an annular member forming a top portion for the tank, a cylindrical member of insulating material joining said bottom and said top tank portions, and a plate-like member forming a cover for the tank. 105

3. In an electric transformer, a metallic member forming a tank bottom portion, a metallic member forming a tank upper portion, an insulating member separating said bottom and said top tank portions, a high voltage winding arranged within the tank, said high voltage winding being substantially the same height as said insulating member, and a low voltage winding arranged in inductive relation to said high voltage winding. 110 115

4. In an electric transformer, a metallic member forming a tank bottom portion, a metallic member forming a tank upper portion, an insulating member separating said bottom and said top portions, a core arranged within the tank, a low voltage winding arranged on said core, and a high voltage winding arranged in inductive relation adjacent said low voltage winding. 120 125

5. In an electric transformer, a metallic member forming a tank bottom portion, a 130

metallic member forming a tank upper portion, an insulating member joining said bottom and said top portions, a core arranged within the tank, insulating members supporting said core from said bottom portion, a high voltage winding arranged on said core and a low voltage winding arranged in inductive relation adjacent said high voltage winding.

6. In an electric transformer, a metallic member forming a tank bottom portion, a metallic member forming a tank upper portion, an insulating member separating said bottom and said top portions, windings arranged in inductive relation within the tank, and means for securing uniform potential drop over said windings arranged adjacent thereto.

7. In an electric transformer, a metallic member forming a tank bottom portion, a metallic member forming a tank upper portion, an insulating member separating said bottom and said top portions, a high voltage winding arranged within the tank, the terminals of said winding being connected with said top and said bottom portions of the tank, and a low voltage winding arranged in inductive relation with said high voltage winding.

30 In testimony whereof I have hereunto subscribed by name this 27th day of May A. D. 1929.

AUGUST MEYERHANS.
